UNITED STATES PATENT OFFICE.

CHARLES H. SMITH, OF ROCKFORD, ILLINOIS.

FOLDING GO-CART.

No. 887,858.

Specification of Letters Patent.

Patented May 19, 1908.

Application filed April 27, 1906. Serial No. 313,913.

To all whom it may concern:

Be it known that I, CHARLES H. SMITH, a citizen of the United States, residing at Rockford, in the county of Winnebago and State of Illinois, have invented certain new and useful Improvements in Folding Go-Carts, of which the following is a specification.

This invention relates to folding go-carts or baby carriages, and one of its objects is the production of such a carriage which shall be reducible to very small compass.

Another object of the invention is the simplification of folding carriage construction with a view to lightness, cheapness, and ease of manipulation.

In the accompanying drawings, Figure 1 is a perspective view of a folding go-cart embodying the features of my invention. Fig. 2 is a detail view of one of the wheel-carrying brackets and the means for locking it in operative position. Fig. 3 is a detail view of said wheel-bracket locking-means.

In the construction of a go-cart embodying the features of this invention I form an integral supporting framework out of a rod or wire of suitable gage, said framework comprising a carriage bed consisting of the base bars 1 and the lower end bar 2 connecting said base bars together, and a seat-support consisting of the side bars 3 and the upper end bar 4 uniting said side bars. The carriage bed and the seat support are flexibly connected together at their forward ends by reason of their being formed integral as hereinbefore stated. Being formed of resilient material, the carriage framework may be folded or collapsed by drawing the rear-ends of the carriage bed and the seat support together. A hook 5 adapted to engage the end bar 4 is pivotally mounted upon the end bar 2 for locking the frame in the folded position.

The wheels 6 are of any desired construction, each being rotatably mounted upon a stub shaft 7 carried by a bracket 8. The brackets 8 are slidably mounted upon the base bars 1, each bracket comprising two diverging arms provided at their upper ends with sleeves 9 and 10 adapted to surround the base bar. In one end of the sleeve 9 of each of the wheel-brackets are formed two locking grooves 11 and 12, said grooves extending at right angles to each other and

being adapted to receive a locking pin 13 fixed in the base bar 1. A coiled spring 14 surrounding the base bar 1 and extending between the pin 13 and the sleeve 10 of the rear wheel-bracket 8 tends to move said wheel-bracket 8 in the direction to place the pin 13 in one of the locking grooves 11 and 12. The two wheel-brackets 8 on each side of the carriage bed are connected to move together by means of a rod 15 secured to said brackets in any suitable way, as by bending the ends of said rod about the stub shafts 7.

A seat 16, of any preferred construction, is attached to the side bars 3. Said seat is herein represented as formed of canvas or any other suitable material. A foot rest 17, which also may be of canvas, is attached to the base bar 1 in proper position with relation to the seat 16. A handle 18 is pivotally connected to the upper end bar 4, said handle being formed of an integral piece of wire or rod, the end portions of which wire are wrapped about the end bar 4 to form pivotal bearings 19 for the handle, and the extreme ends of the bar being bent to underlie the side bars 3 and form limiting stops 20 for the downward movement of said handle.

For convenience in operating the folding wheel brackets 8, the rear brackets 8 are connected together by means of a bar 21, said bar in this instance being pivotally connected with the sleeves 10 of said brackets by being bent to form rings 22 lying within peripheral grooves 23 in said sleeves. The bar 21 is pivotally connected with the hook 5, the pivotal connection being herein shown as formed by coiling about said hook the middle portion of said bar.

The carriage is folded by sliding the wheel-brackets 8 forward, against the force of the springs 14, until the sleeves 9 have been withdrawn from the locking pins 13, when the brackets 8 may be swung inward to a position at right angles to the operative position. When the brackets 8 are released the springs 14 move the sleeves 9 into locking engagement with the pins 13, said pins entering the grooves 12. The framework is then folded by drawing the seat support and the carriage bed together and locking them in such position by means of the hook 5, and the handle 18 is tilted upward over upon the side bars 3.

It is apparent that various changes may be made in the construction and arrangement

of the parts herein shown and described. I therefore desire not to limit myself to the precise details herein set forth.

I claim as my invention:

5. 1. An integral folding go-cart frame consisting of a carriage bed and a seat support both formed from a single length of wire.
10. 2. An integral folding go-cart frame consisting of a carriage bed comprising two base bars and a seat support comprising two side bars, the side bar and the base bar at each side of the cart being connected together at one end, the parts connecting said bars being resilient, said pair of bars being foldable toward and into a position relatively near each other.
15. 3. In a folding go-cart, in combination, a carriage bed and a seat support connected together at their forward ends and each arranged to fold as a whole against the other, said carriage bed and said seat support being formed from an integral piece of wire and means for securing said carriage bed and said seat support in such folded position.
20. 4. In a folding go-cart, in combination, a supporting framework comprising base bars; wheel-supporting members rotatably mounted on said base bars; means for locking said wheel-supporting members in position; and means for moving said wheel-supporting members to unlock them.
25. 5. In a folding go-cart, in combination, a supporting framework comprising two base bars; a plurality of wheel-supporting members rotatably mounted on each of said base bars; means for connecting the wheel-supporting members on each base bar to move together; means for locking said wheel-supporting members in position; and means for connecting the wheel-supporting members on both base bars to move together.
30. 6. In a folding go-cart, in combination, a base bar; a wheel-supporting member comprising a sleeve rotatably mounted on said base bar; said sleeve having two locking grooves therein; a locking pin on said base bar adapted to enter said grooves; and a spring tending to bring said sleeve and said pin into engagement.
35. 7. In a folding go-cart, in combination, a supporting framework comprising base bars, and wheel brackets comprising two arms, each of which arms is provided with a sleeve adapted to surround said base bars, said base bars having locking members thereon adapted to engage said sleeves.

8. In a folding go-cart, in combination, a supporting framework comprising two side bars and an end bar connecting said side bars together; and a handle pivotally mounted on said end bar and provided with limiting stop portions adapted to engage said side bars.

9. In a folding go-cart, in combination, a supporting framework comprising two side bars and an end bar connecting said side bars together; and an integral handle formed of wire, portions of said wire being wrapped about said end bar to form pivotal bearings for the handle and the ends of said wire being bent to underlie the side bars and form limiting stops for the handle.

10. In a go-cart, in combination, a longitudinally extending base bar; a wheel-supporting bracket mounted upon said base bar and slideable longitudinally thereof; means on said base bar adapted to engage said bracket for locking it in position; and means for holding said bracket in locking engagement with said last mentioned means.

11. In a go-cart; in combination, a longitudinally extending base bar; a wheel-supporting bracket mounted upon said base bar and slideable longitudinally thereof; a locking pin fixed in said base bar; and a spring tending to move said bracket into locking engagement with said pin.

12. In a go-cart, in combination, a supporting framework comprising a longitudinally extending base bar; two wheel-supporting members rotatably mounted on said base bar and longitudinally slideable thereon; means for connecting said wheel-supporting members to slide and rotate together; and means for locking said wheel-supporting members in position.

13. In a go-cart, in combination, a supporting framework comprising two base bars; two wheel-supporting members rotatably mounted on each of said base bars and longitudinally slideable thereon; means for connecting the wheel-supporting members on each base bar to rotate and slide together; means for locking said wheel-supporting members in position; and means for connecting the wheel-supporting members on both base bars to slide together.

CHARLES H. SMITH.
